UNITED STATES PATENT OFFICE.

MAUD A. SWIGERT AND HARRY A. SWIGERT, OF EVANSTON, ILLINOIS.

ENVELOPE.

Application filed July 29, 1918. Serial No. 247,245.

The present invention relates to that class of envelopes that are used for transmitting third class matter through the mails and the object of the invention, stated generally, is to provide an improved envelope of this class.

The postal rules and regulations require that envelopes of this class of mail matter shall be of such construction that their contents may be readily examined by the post office inspectors and, for this purpose, completely withdrawn from the envelope, if necessary, without mutilating the envelope or breaking any seal, however small or of whatever nature, while at the same time efficiency in use requires that the load or contents of the envelope be prevented from accidentally escaping from the envelope while being handled or in transit. Other important desiderata are that the blank may be cut with a minimum waste of stock and that weight be minimized. A minute saving of weight in a single envelop may not be sufficient to save the sender an additional unit rate of postage but when this small saving in weight is multiplied many times, as in the transportation of the immense volumes of mail matter that are handled by the postoffice department, it becomes significant.

From a commercial standpoint, low cost of production is an essential desideratum, and to this end the blank is made of such shape that it may be cut from the stock to the best possible advantage.

The term "end" is used in this specification more for the sake of simplicity and convenience in describing some of the several forms of envelopes shown in the drawings, as embodying one or more of the several features of the invention, and is not to be taken or understood and construed in its strict and more popularly accepted sense, which would tend to limit the invention and this specification to an envelope the top and bottom sides of which are of greater length than the end sides and the novel features hereinafter described are applied to the end sides, commonly called the "ends". In all cases the envelope has four "sides" and in many instances throughout this specification, excepting only where the context makes a more exact reading necessary to the sense, the term "side" may be read for the term "end" the spirit and intent of

the invention being that the hereinafter described novel features may be at any side compatible with the accomplishing of the functions aimed at, this being left to the skill and discretion of the manufacturer.

To these ends the present invention may be embodied in an envelope having a front, a fold joining one end of this front and reflexed so as to lie against its inner face, a back, to the (in the completed envelope) corresponding end of which said fold is secured by small dabs of gum located at points at or near the top and bottom thereof respectively, and a loose flap joining the back at the same end of the envelope, said loose flap being reflexed so as to lie against the inner face of the back and between it and the fold aforesaid, the three other sides of the envelope being closed in any desired manner.

Or, within the scope of the invention these conditions may be reversed. That is to say, the open-end fold of the envelope may join the back and the loose flap may join the front, but this would be less desirable because it would render the loading of the envelope more difficult.

An envelope embodying the invention has certain other minor features of construction or may lack some of those mentioned, all as hereinafter described with reference to the accompanying drawings which are hereby made a part of this specification and in which:—

Figure I is a diagram of a blank from which is made the improved envelope, with all of its parts and features, of what, for the purposes of this application, is selected as a basis for description.

Fig. II is a similar view after the end folds and loose flap have been folded against the inner faces of the front and back which they respectively join.

Fig. III is a view of the rear side of the complete envelope in readiness for loading but before the sealing flap is folded down.

Figs. IV, V and VI are fragmentary views of blanks of the open end of an envelope embodying some features of the invention under slight modifications.

Fig. VII is a view of the rear side of an envelope in readiness for loading, embodying some features of the invention under other modifications.

Fig. VIII is a diagram of the blank from which the envelope shown in Fig. VII is made.

Fig. IX is a view of the rear side of an envelope in readiness for loading, embodying the invention under still other modifications.

Fig. X is a diagram of a blank from which the envelope shown in Fig. IX is made.

Fig. XI is a diagram of the same blank at an intermediate stage in the process of making the envelope shown in Fig. IX from the blank shown in Fig. X.

15 In the drawings corresponding parts of the completed envelopes and of the blanks from which they are made bear similar reference numerals.

The outlines of the blanks from which 20 the several envelopes shown in the drawings are made are shown by full lines. When the blank is folded upon the rectangularly disposed dotted lines 1, 2, 3 and 4 it forms the front, 5, the back, 6, the sealing 25 flap, 7, the closed-end folds, 8 and 9, the open-end fold, 10, and, the loose flap 11. The back consists of a portion additional to the flaps and is substantially conterminous with the front. In the process of folding, 30 the blank shown in Fig. I, it is first folded upon the lines 3 and 4, completely across from top to bottom. This brings the closed-end fold 8 and the open-end fold 10 against the inner face of the front, 5, and the 35 closed-end fold, 9, and the loose flap, 11, against the inner face of the back, 6. Paste, 40 gum, or any desired adhesive material may then be applied to the sealing flap, 7, as shown at 12, to one or both of the closed-end flaps, 8 and 9, as shown at 13, and to the open-end fold, 10, the latter in the form of small dabs, 14, located at points at or near the ends thereof, or directly to the back, 6, at corresponding points. Then when the blank 45 is folded on the line 2 the inner face of the back, 6, is brought against the inner face of the front, 5, throughout the greater part of their areas, the end folds, 8 and 9 are brought against each other and the envelope 50 thereby permanently closed at this end, the loose flap 11, is brought against the open end fold, 10, so as to lie between it and the inner face of the back and the latter is brought against the dabs, 14, reaching them 55 through cut-away portions or notches, 15, with which the loose flap, 11, is provided.

As to all features so far described (numbered 1 to 15 inclusive) this is all true of all of the figures of the drawings, excepting that in Figs. VII and VIII the front and back are arranged end to end, instead of one above the other, and are joined by a fold upon the line 3 thus forming a permanently closed end opposite the open end of the envelope, and the folds 8 and 9 join

the front and back, respectively, along their longer bottom sides instead of along their shorter end sides; and the loose flap 11 joins the back, through a fold along the line 4^a located at the side of the blank opposite the 70 side which the fold 10 joins instead of at the same side.

It is also true of Figs. IX to XI, excepting in the respect of such changes as are necessitated by joining the closed-end fold 75 10 and loose flap 11 to the front and back, respectively, through folds upon lines extending along their longer bottom sides instead of along their shorter end sides, and, having both of these shorter end sides permanently closed.

The primary object of the invention is to provide some means hereinafter called a tongue by which the open-end fold 10 and with it the loose flap, 11, will, when the front and back are spread apart, be carried by the back and by it held a sufficient distance away from the inner surface of the front while the envelope is being loaded, to insure that the enclosure will, with ease and certainty pass between the inner face of the front and the part lying against it, and at the same time be prevented from being accidentally forced out of the open end of the envelope. This is the principal feature that is common to all of the various forms or modifications of envelopes embodying the invention whether the notch be present or not.

In the form shown in Figs. I, II and III 100 each of the notches 15, is of approximately L-shape, one branch extending from the end of the loose flap and joining the other branch, which latter extends quite from the line of the fold through which the loose flap joins the back, inward toward, but not to, the inner edge of the loose flap, resulting in a tongue 16 of hook-shape which comprises a shoulder, 17, which lies adjacent to the inner side of the dab, 14, and a supplemental tongue 18, that extends outward toward the open end of the envelope and lies between the dab, 14, and the fold through which the front, 5, joins the back, 6, or the sealing flap, 7, as the case may be. 110

Thus when the envelope shown in Figs. I, II and III is completed and ready to receive its load, the loose flap, in its entirety, will lie between the open-end fold, 10, and the back, 6, so that when the front, 5, and back, 6, are spread apart for receiving the enclosure the back will carry the loose flap with it and the loose flap will also be prevented from escaping by reason of its being held between the end fold 10, and the back, 6.

The loose flap is wholly unattached by gum to any part of the envelope so that when, for inspection purposes, the loaded and sealed envelope is squeezed by pressure 130

against the top and bottom edges the loose flap and open-end fold will spread apart and permit its contents to be inspected through the opening thus made: or the enclosure may be completely withdrawn either with or without withdrawing the loose flap and, after thorough inspection, replaced through this same opening.

In replacing the loose flap it is not practicable to readily and quickly replace the supplemental tongue 18 in the space between the open-end fold 10, and the back, 6, and the dab 14 and fold through which the front, 5, joins the back, 6, or sealing flap, 7, as the case may be but in practice this is not essential. It is sufficient if the major part of the loose flap be replaced between the open end fold, 10, and the back, 6, and between the inclosure and the front. This will hold the load in.

The inner edge of the loose flap may be straight from end to end and of considerable width, as shown in Figs. I, II, III and VI to XVI, inclusive, or it may be cut away as shown in Figs. IV and V, for the purpose of saving stock and reducing weight. Likewise the inner edge of the open end fold 10 may be cut away, as shown in Figs. I, II and III for the same purpose, or it may be straight and of considerable width as shown in Figs. IV, V, VII, VIII and IX to XI (the latter for the more firmly holding the enclosure) or it may be quite narrow throughout its length as shown in Fig. VI. The notch 15 and resulting tongue 16 of the loose flap may be variously shaped. The one shown in Figs. I, II, III, and its mode of operation have already been described.

In Figs. IV and V the notch opens at the end of the loose flap and the supplemental tongue projects in the same direction, providing a shoulder 17 which is substantially parallel with the open end of the envelope and therefore substantially perpendicular to the line of strain that is put upon the loose flap by the outward pressure put upon it from within. This offers a firm resistance to the accidental forcing out of the flap. Its intentional withdrawal from without for the purpose of inspection, is facilitated and the tearing of the tongue prevented by forming the shoulder on a slope the trend of which is outward toward the end of the tongue and away from the open end of the envelope. This slope may be produced by flaring the notch outward and this may be done by rounding off its edges as shown in Figs. IV, V and IX to XI, or making it of substantially V-shape, as shown in Fig. VI. When the open end of the envelope is opened up for inspection purposes the tendency will be to bow the loose flap and draw the sloping portion of the supplemental tongue into contact with the dab 14.

In Figs. VII and VIII the notch is rec-

tangular and at one side extends quite to the line of the fold joining the loose flap to the back, and at an adjacent side extends quite to the end of the loose flap, resulting in a tongue 16 having a shoulder 17 which is perfectly straight throughout and is substantially perpendicular to the line of strain tending to force the loose flap out.

In all of the forms of envelope embodying the invention, including the form now to be described, as well as those above described, the envelope has a front and a back, a loose flap joining one end of either the front or the back and a tongue on the loose flap engaged by the back.

Only one notch and its accessories has hereinbefore been mentioned. This was for the sake of convenience and simplicity of description, but it is manifest that while the one located near one of the four sides of the envelope may suffice it is believed that it will be better to use also a second one located at each end of the loose flap, as shown in the drawings.

What we claim as new is:

1. In an envelope of the class described, a back member, a front member, a sealing flap, a loose flap hinged to the end edge of one of said members, an end fold hinged to the corresponding end edge of the other of said members, a dab of glue on the end of said end fold adjacent the sealing flap cementing said end of the end fold to the first mentioned member, the loose flap being so cut away at its ends adjacent the dab of glue that when lying between the front and back members it interlocks with said dab.

2. An envelope having a front, a back, a loose flap joining one and a fold joining the other of them, both at the same side of the envelope, said fold and flap lying between the front and back thereof, said loose flap being cut away to form a tongue and a dab of adhesive material uniting the fold and back at a point adjacent to said tongue.

3. An envelope having a front section and a back section secured along one edge and side, a sealing flap secured to the front along the other side edge, an end fold joining the other end of the front section, a loose flap joining the corresponding end of the back section, said fold and back lying between said front and back sections, the fold being attached by a dab of glue at its end adjacent the sealing flap to the back section, and a tongue on the loose flap partially encircling the dab of glue whereby when the envelope is spread at the open side for the insertion of matter the end fold and loose flap move with the back section.

4. An envelope having a front, and a back, a fold, and a loose flap lying between and joining said front and back, respectively at the same end of the envelope said

loose flap having a notch resulting in a tongue having a sloping shoulder, and a dab of adhesive material joining the back and fold through said notch and lying adjacent to said shoulder.

5. An envelope having back and front sections attached along one side and one end and a sealing flap attached along the other side of the front section, a flap on the other 10 end of the front section and attached at the end adjacent the sealing flap to the back section and a flap attached to the back section at the latter said end, cut away at its end adjacent the sealing flap to avoid the attachment 15 between the first mentioned flap and the back section and loosely turned in between

the first mentioned flap and the back section.

6. An envelope comprising a front section, a back section, a sealing flap, and a flap hinged to one of said sections at an end 20 thereof but turned in between said sections, a dab of glue on the end of said flap adjacent the sealing flap adhering to the other said section, a flap on the other said section loosely turned in between the same and the 25 flap of the first said section extending substantially across the end of the envelope but cut away in an area corresponding to the dab of glue.
